CHARLES CORNELIUS HULL, OF WILLIAMSBURG, NEW YORK.

Letters Patent No. 88,876, dated April 13, 1869.

MECHANISM FOR TRANSMITTING MOTION.

The Schedule referred to in these Letters Patent and making part of the same.

To all whom it may concern:

Be it known that I, CHARLES CORNELIUS HULL, of Williamsburg, in the county of Kings, and State of New York, have invented a new and improved Engine for Transmitting Power and Motion; and I do hereby declare that the following is a full, clear, and exact description thereof, which will enable others skilled in the art to make and use the same, reference being had to the accompanying drawings, forming part of this specification.

This invention relates to a new and improved combination of mechanical appliances, as pendulum-levers, wheels, working-beam, and cranks, whereby power is applied and transmitted from one to the other in a very advantageous manner, and whereby I am enabled to change a rotary from a pendulum motion, with a great increase of speed, for the propulsion of machinery, and for all purposes to which the combination and improvement is applicable.

In the accompanying plate of drawings—

Figure 1 represents a side elevation of the engine, showing the side which bears the first, or actuating pendulum.

Figure 2 is an elevation of the opposite side of the engine, showing the method of transmitting the power from one section to another.

Similar letters of reference indicate corresponding parts.

A represents the rod of the pendulum, by which motion and power are imparted in the first instance.

B represents the frame to which the moving parts of the engine are attached.

C is the bed-plate, upon which the frames of the sections stand.

In this example of my invention I show an engine of two sections.

D represents the first and E the second section, but it will be seen that the motion and power may be transmitted from the second to a third and fourth section, and so on, as may be desired, with an increase of lever power or speed.

Motion is imparted by the pendulum to the shaft F, by the gear-wheels g h.

The cogs of the two wheels g h engage with each other, as shown in the drawing, and give the shaft F a rocking motion.

I is a working-beam on the shaft F, by which motion is conveyed to the crank J by the pitman K.

This crank turns the fly-wheel L, the shaft of which is provided with another crank m, seen in fig. 2.

The power and motion are conveyed from the crank m to the section E by the connecting-rod N, which is attached to the pendulum O at the point p, where the connection is adjustable, as seen in the drawing.

This pendulum O is fast on a shaft, q, and as it oscillates it imparts a rocking motion to the shaft R of the working-beam S, by means of the gear-wheels T U.

The motion is transferred from the working-beam S by the pitman V, on the shaft W of the fly-wheel X and the crank Y.

It will be seen that a rotary motion is given the fly-wheels L and X for the transmission of power and motion to machinery requiring rotary motion.

The wheel a' on the shaft of the fly-wheel X, and the wheel c' in the frame B of the section E, are speed-wheels, which may be varied in size and multiplied in number to obtain any required speed for driving machinery.

The arm d', on the fly-wheel X of the section E, is for transmitting the power and motion to other sections of similar construction, which may be added to any required extent.

I do not, of course, confine myself to the particular proportions of the engine as given in the drawing, my object being merely to show the general plan I have invented for transmitting power and motion.

The method of transmitting the power of the pendulum and the motion thus acquired from one section to another, and from the section in machinery, have been sufficiently described.

Having thus described my invention, I claim as new, and desire to secure by Letters Patent—

The combination of the pendulums A and O with the working-beam S, and the gear-wheels, cranks, and rods connected therewith, substantially as herein shown and described, and for the purpose set forth.

CHARLES C. HULL.
